UNITED STATES PATENT OFFICE.

JAMES S. ROBINSON, OF NORTH EAST, PENNSYLVANIA.

IMPROVEMENT IN ADJUSTABLE ORGAN-TREADLES.

Specification forming part of Letters Patent No. 177,962, dated May 30, 1876; application filed November 12, 1875.

To all whom it may concern:

Be it known that I, JAMES S. ROBINSON, of North East, in the county of Erie and State of Pennsylvania, have invented certain new and useful Improvements in Adjustable Treadles for Organs, &c.; and I do hereby declare that the following is a full, clear, and exact description thereof, which will enable others skilled in the art to which it pertains to make and use the same, reference being had to the accompanying drawing, and to the letters of reference marked thereon, which form a part of this specification.

The nature of my invention consists in providing an organ, melodeon, or other instrument with a treadle so constructed that the same can be as easily operated by a person of low as one of high stature.

My invention may be divided into two parts: first, the mode of adjusting the treadles to various heights; second, the mode of adjusting the treadle to the webbing or cord which connects it with the exhaust or bellows.

My invention is represented in the accompanying drawing as follows: Figure 1 is a section view, taken lengthwise of the treadle and crosswise of the instrument, and shows the first part of my invention entire, and the mode of accomplishing the second part.

The following is a full description of my devices: A is the base-board of the instrument, and A' is the projection of the base-board, usually made at the place where the treadles attach. C is a part of the front board of the case. B represents the exhaust or bellows.

As before stated, the first part of my invention relates to the mode of adjusting the treadles to various heights, and may be described as follows: The treadles are represented by the letter a. These are hung at the heel by a hinge, e, to a frame, b, which is hung to the base-board A by a hinge, e', at its inner edge or "toe." At its outer edge or "heel" is attached, by a pin, a sustaining-bar, c, which is notched or ratcheted, and engages with a pin, h, in the front board C. There are two of these bars c, one at each end of the frame—that is, at each side of the treadles.

When the treadles are raised, as is shown by the dotted lines, the frame b is carried up at

its outer side or heel, and the sustaining-bar c slides upon the pin h, and, the ratchets becoming engaged, the treadles are sustained at the proper point of elevation.

It will be seen from the above description, obvious to any one skilled in the art to which this invention relates, that any degree of elevation can be had, this being entirely regulated by the length of the ratchets in the bar c.

I do not wish to be confined to the particular form and mode of ratcheting the sustaining-bars c herein shown, for it is obvious that many equivalent modes may be devised.

When the treadles are made adjustable it becomes necessary to have the treadle port, or opening through which the treadles work, also adjustable, or else when the treadles are low down the opening is too great, and exposes the inside of the case too much to view; or else when the treadles are high up there will not be room for the feet. To obviate this I use a curtain-board, d, which is attached to the two sustaining-bars c, at the proper height above the treadle, by a pivot-pin, and its upper edge slips into an opening behind the front board C, and is kept in position there by a guide, g. Now, when the treadles are raised the curtain-board is also carried up by the sustaining-strips c, as shown by dotted lines.

When treadles are made adjustable it is necessary to provide a means of so attaching the treadles to the webbing that there will be no "slack"—that is, to so attach them that they will operate upon the webbing as perfectly at one point as another. This is provided for in the second part of my invention, as clearly shown in Fig. 1. The webbing is represented by E. It is attached to the heel of the frame b, and then passes through a loop, f, in the board A'; thence under the frame b toward the back of the instrument, where it passes through another loop, f'; thence up to the top of the exhaust B, where it passes through another loop, f''; thence to a point on the front board C above the treadles, where it passes through another loop, f''', and thence down to the toe of the treadle a, where it is attached. Now, by observing the dotted lines it will be seen that the "pull" upon the webbing is the same no matter at what point the treadles may act.

What I wish to claim as new, and secure by Letters Patent, is as follows:

1. The treadle *a*, secured by hinge to a frame or platform, *b*, hinged at its opposite or rear side to the case *A*, in combination with a ratcheted sustaining-bar, *c*, substantially as described.

2. In combination with the subject-matter of the preceding clause of claim, the webbing *E*, attached to the heel of the frame *b*, bellows *B*, toe of the treadle *a*, by means of loops and pulleys *f f' f'' f'''*, one of which latter is secured to said bellows, substantially as set forth.

3. The front of an organ case provided with a pedal-port and the sliding curtain-board *d*,

all constructed and arranged to operate substantially as set forth.

4. In combination with the treadle, base-board, bellows, and case of an organ, the webbing *E* and loops or pulleys *f f' f'' f'''*, all constructed and arranged to operate substantially as described.

In testimony that I claim the foregoing as my own I affix my signature in presence of two witnesses.

JAMES S. ROBINSON.
